UNITED STATES PATENT OFFICE.

ERNEST SHAW, OF ROSETTE, UTAH.

HOLDER FOR GRAPHIC INSTRUMENTS.

Application filed February 16, 1925. Serial No. 9,450.

To all whom it may concern:

Be it known that I, ERNEST SHAW, a citizen of the United States, and a resident of Rosette, county of Box Elder, State of Utah, 5 have invented a certain new and useful Improvement in Holders for Graphic Instruments, of which the following is a complete specification.

This invention relates to a holder for 10 graphic instruments such as a pen, pencil, brush or stylus where it is desired to secure a uniform weight on the operating point and a consequently uniform line regardless of whether a down, up or lateral stroke is 15 being made.

Another object is to produce a holder of 20 the general character outlined having means whereby the holder can be adjusted to accommodate the angle at which various writers may habitually hold the graphic instrument.

A further object is to provide a holder of 25 the general character mentioned which may be readily provided with additional weight to press harder on the working point.

A still further object is to produce a graphic instrument holder of the character outlined which is of strong, simple, durable and inexpensive construction; and in order 30 that it may be fully understood, reference is to be had to the accompanying drawing, in which:—

Figure 1 is a central vertical section taken 35 through a holder embodying the invention, it being noted that it is illustrated in connection with a writing pen, the body of the pen being somewhat shorter than would be the case in actual practice.

Figure 2 is a section similar to that of 40 Figure 1 but at right angles thereto.

Figure 3 is a side elevation of the pen as 45 it will appear when not in use.

Figure 4 is a section on the line IV—IV of Figure 1.

In the said drawing, where like reference 50 characters identify corresponding parts in all of the figures, 1 indicates the barrel of a fountain pen equipped with the customary nib 2 and internal ink sack 2^a, said barrel 55 being of any common or ordinary type and of cylindrical form. Molded integrally with the barrel, on opposite sides thereof and extending laterally therefrom, are a pair of ribs 3.

The pen 1 is received within a holder 4 having a bore of sufficient diameter to slid-

ingly receive the pen, and adjacent the point of the pen, said holder has an enlarged internal recess 6 for a purpose which will hereinafter appear. Communicating with said recess are the ends of a pair of oppositely disposed internal slots 7 for the reception of the ribs 3 of the barrel of the pen, it being understood that the slots are of greater length than the ribs. 65

The internal face of the recess 6 is threaded for the reception of a threaded sleeve 8 having its bore of sufficient diameter to snugly receive the barrel of the pen without offering any appreciable resistance to 70 the sliding thereof. The barrel of the pen is thus free for sliding back and forth within the holder, being limited in its rearward movement through contact of the rear ends of the ribs 3 with the rear ends of the slots 75 7, and in its forward movement through contact of the front ends of the ribs 3 with the collar 8, the interlocking ribs and slots also serving to prevent rotation of the pen barrel. By threading the sleeve 8 back and 80 forth, the range of forward movement of the pen may be adjusted to fit varying conditions as will hereinafter appear.

Secured to the holder 4 at a point in line with the pen nib is a fixed guide 9 bowed 85 out to permit the pen cap 10 to be screwed on the end of the holder as common, and said guide is equipped with a ball extremity at its lower end. When the device is in use the guide 9 will be in constant contact with 90 the writing surface and transmits all of the pressure of the writer's hand direct to such surface. The pressure on the writing point is thus that of the weight of the pen barrel alone and a uniform line is thus secured, 95 although, if desired, suitable weights may be inserted in the end of the holder as at 11 to press down on the pen barrel and increase the pressure on the point to trace a heavier line. 100

In the use of the device, the guide 9 is always maintained in contact with the writing surface, the pen point being elevated at the end of a word and the like, by a slight movement in the direction indicated by the 105 arrow "a" around the end of the guide. This movement effects the upward sliding movement of the holder until the sleeve 8 abuts the ends of the ribs 3 and consequently effects upward movement of the pen point in 110 the direction of the arrow "b".

In this regard, it is to be noted that the

degree of movement of the holder necessary to elevate the point may be adjusted by manipulation of the sleeve 8, this adjustment also being necessary to compensate for the 5 different angles at which various users may hold the pen.

In actual use, the pen barrel will possess but a slight range of sliding movement, as the angle of the pen in writing is seldom 10 shifted to any great extent. The proportion of the parts will be such that the end of the barrel of the pen will be just about parallel with the end of the holder when the pen is at its limit of inward or inoperative position. 15

As it may be desirable at times for the operator to press with a greater force of the nib of the pen than that of the weight of the barrel sleeve, a friction plug 12 (see Figure 1), is mounted in the holder 4 and slightly projects therefrom. The inner end of said plug terminates in an enlarged face 13 for engagement with the barrel 1 of the pen. With this construction it will be apparent 20 that the operator can arrest the sliding movement of the pen when he desires to cross a letter "T" or the like, by imposing pressure on the projecting end of the plug. 25

From the above description it will be apparent 30 that I have produced a holder of the character outlined which possesses all of the features of advantage set forth as desirable, and while I have described and claimed the preferred embodiment of the same, I reserve 35 the right to make all changes properly falling within the spirit and scope of the appended claims.

I claim:

1. A holder, a guide on said holder, a 40 graphic instrument freely sliding in said holder, means for preventing the rotation

and limiting the sliding movement of said instrument in one direction, and adjustable means for limiting the sliding movement of the instrument in the other direction. 45

2. A holder having an internal slot, a graphic instrument freely sliding in said holder and having a rib engaging the slot of the holder, an external guide secured to said holder, and an adjustable sleeve adapted 50 to be adjusted to limit the sliding movement of the instrument in one direction within predetermined limits.

3. A holder having an internal slot, and an internal recess at one end, a graphic instrument freely sliding in said holder and having a rib engaging the slot of the holder, and an adjustable sleeve in said holder recess adapted to limit the sliding movement 55 of said instrument in one direction.

4. A holder, a guide on said holder, a graphic instrument freely sliding in said holder, means for preventing the rotation and limiting the sliding movement of said instrument in one direction, adjustable 60 means for limiting the sliding movement of the instrument in the other direction, and friction means for preventing the sliding movement of said instrument.

5. A holder having an internal longitudinal slot and at one end an enlarged threaded recess, a graphic instrument freely sliding in said holder and having a rib engaged with the slot thereof, a sleeve threaded in the end recess of said holder, and a manually operable friction device carried by the holder and adapted to apply friction against said graphic instrument. 70 75

In witness whereof I hereunto affix my signature.

ERNEST SHAW.
